United States Patent Office

Des. 224,105
Patented July 4, 1972

224,105

WATER FILTER OR SIMILAR ARTICLE

Michael A. Turturro, 2020 Idaho Ave.,
Santa Monica, Calif. 90403

Filed Dec. 11, 1970, Ser. No. 26,407

Term of patent 14 years

Int. Cl. D23—01

U.S. Cl. D23—4

FIG. 1 is a perspective view taken from the front and left side of a water filter or similar article embodying my new design;

FIG. 2 is a right side elevational view thereof;

FIG. 3 is a rear elevational view thereof;

FIG. 4 is a top plan view thereof; and

FIG. 5 is a bottom plan view thereof.

I claim:

The ornamental design for a water filter or similar article, as shown.
